UNITED STATES PATENT OFFICE

WILLIAM JACKSON SCHOONOVER, OF DES MOINES, IOWA.

GEARING DEVICE.

1,022,881.

Specification of Letters Patent. Patented Apr. 9, 1912.

Application filed December 24, 1906. Serial No. 349,214.

To all whom it may concern:

Be it known that I, WILLIAM J. SCHOONOVER, a citizen of the United States, residing at Des Moines, in the county of Polk and State of Iowa, have invented new and useful Improvements in Gearing Devices, of which the following is a full, clear, concise, and exact description, reference being had to the accompanying drawing, forming a part of this specification.

My invention relates to improvements in washing machines, and its object is to furnish an improved construction and arrangement of operating parts in such machines, with a view to economy in the cost of manufacture and durability and efficiency in use.

To accomplish the foregoing objects, my invention consists in the features of construction and in the combination of parts and arrangement of devices hereinafter described and claimed.

Other objects and advantages of my invention will be brought out and made to appear in the following specification, reference being had to the accompanying drawings which illustrate one form in which my invention may be practically embodied, and in which,

Figure I is a top plan view of the tub of the washing machine embodying my invention, which view shows the operating parts mounted upon the door of the tub, mechanically associated with the operating lever pivotally mounted on the side of the tub; Fig. II is a right end elevational view of the parts shown in Fig. I; Fig. III is a partly sectional view taken on the dotted line III—III of Fig. I; part of the tub being broken away; Fig. IV is a view taken on the dotted line IV—IV of Fig. III; Fig. V is a detail partly broken and in section of the operating lever and shows the loose mechanical connection of the pitman to the lever; Fig. VI is a view in perspective of the four-arm bearing plate; Fig. VII is a view taken on line VII—VII of Fig. III.

Referring now to the drawings, it will be seen (Figs. I and II) that the gearing for actuating the agitator in the tub 3 is mounted on the hinged door 2, and that this gearing is operatively associated with the lever 4 pivotally mounted on a bracket 5 which is secured to the side of the tub. A four-arm bearing plate 6 is mounted on the door 2 and may be secured thereto by the bolt 7, and a cross piece 9 has flanged end supports

10 mounted on opposite arms of said bearing plate and secured to the door 2 by bolts 11 passing through the flanges and through the arms of the plate. A pinion 12 journaled on the bearing plate and below cross piece 9 has a shaft 13 which extends through the bearing plate and the door into the tub where it is secured to a wide flattened extension 14 at its lower end, which extension fits loosely into the agitator head 15 so that the latter may move longitudinally of such extension. In mesh with the pinion 12 is a substantially elliptical member 16 which is provided with teeth on its interior centrally of one of its long sides and is pivotally mounted at the center part 18 of its other long side, on a stud 19, of suitable material, which is secured to one of the arms of the bearing plate. To provide a reduced amount of bearing surface for the elliptical member 16 a portion 20 of the bearing plate is ridged. On the long side opposite to its pivotal point the elliptical member 16 is provided with a short arm 17 to which is pivoted one end of the pitman 21. The pitman rests on and has its movement guided by the bracket 22 secured on the top of the tub at its front part. The other end of the pitman is shaped substantially like an inverted U whereby it is adapted to fit over a round cross bar 24 secured to the bifurcations of the bracket 25 on the operating lever so that a loose mechanical connection may be effected between the pitman and the operating lever and thus providing a means for readily associating the pitman operatively with the lever and for automatically disengaging it from operative connection with the lever upon the raising of the door 2 of the tub. The walls of the guiding portion of the bracket 22 diverge from the center to the ends to permit free angular movement of the rod on the bracket.

The operating lever 4 at its lower end below its pivotal point is provided with an extension 26 which abuts against the lower portion of the bracket 5 to limit the downward movement of the lever when it is disengaged from the pitman 21.

The operation of the parts thus far described, is as follows: When the door of the tub is opened to place the contents therein, the pitman associated with the operating lever is automatically detached therefrom; after the contents have been placed in the tub and the door is closed, the inverted U-

shaped end of the pitman 21 is fitted over the cross bar 24 of the bracket 25 on the operating lever, and if, now, the operating lever is oscillated, an alternating rotary motion is communicated to the agitator head which is transmitted to the contents in the tub.

In order to render the operation of the working parts easier and to produce a 10 steadyng effect in operation, a fly wheel may be provided and associated with the above arrangement as follows: A gear wheel 27 rotatably mounted on a stud 28 at the end of one of the arms of the bearing 15 plate is connected to the pitman 21 by means of rod 29 which is pivoted at one end 30 to a spoke 31 of the gear wheel, and at the other end is pivoted near the end of the pitman 21 at 32. The fly wheel 33 is 20 rotatably mounted on a ball bearing 34 on the stud 19 and is provided, on its lower side, with an extended hub 35 terminating in a pinion 36 which meshes with the gear wheel 27.

25 It will thus be seen, with the above arrangement of mechanism, that when the operating lever is oscillated, an alternating rotary motion is communicated to the agitator head while a continuous rotary motion 30 is communicated to the fly wheel.

As will be gathered from the foregoing, the tub 3 constitutes one supporting means for my novel mechanism.

While I have herein described one form 35 in which I have worked out my invention for practical purposes, I do not desire to be

limited to the exact details of construction shown and described since many changes in the details of construction and arrangement and combination of parts as set forth will 40 occur to a person skilled in the art and which are intended to fall within the purview of the claim appended hereto.

Having thus described my invention, what I claim as new and desire to secure by Letters Patent, is:

An operating device for washing machines, comprising a body, an upright mounted in the body, a pinion thereon, a rack on top of the body in mesh with the 50 pinion, a pitman connected with said rack and having its other end provided with a vertically arranged slot open at its bottom, a gear wheel mounted above said rack, a balance wheel above said gear wheel, a pinion connected with the balance wheel, and in mesh with said gear wheel, a pitman pivoted to said gear wheel and also to the first mentioned pitman near its outer end and a lever fulcrumed to the body and having a 55 lateral extension provided with a pin designed to enter the slot in the pitman so that the pitman may be elevated to disengage it from the operating lever, for the purposes stated.

In witness whereof, I have hereunto subscribed my name in the presence of two witnesses.

WILLIAM JACKSON SCHOONOVER.
